(57) **CLAIM**

The ornamental design for implant tool, as shown and described.

DESCRIPTION

FIG. 1 is a front, top, right perspective view of an implant tool, showing the new design, shown with the unclaimed environment of a counter torque wrench;

FIG. 2 is a rear, bottom, left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and

FIG. 8 is a bottom view thereof;

FIG. 9 is a front, top, right perspective view of the tip of FIG. 1, shown with the unclaimed environment of an abutment inserter;

FIG. 10 is a rear, bottom, left perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The broken lines of uneven length shown in the drawings illustrate the boundary of the claimed design and form no part thereof. The broken lines of even length shown in the drawings illustrate portions of the implant tool that form no part of the claimed design.

1 Claim, 16 Drawing Sheets
